SUITCASE AND TRAY

Ted Wilt, Evanston, Ill.

Application July 27, 1954, Serial No. 445,955

13 Claims. (Cl. 190—41)

This invention pertains to improvements in luggage, such as wardrobe type suitcases or traveling cases, in which garments may be conveniently arranged over hangers, folded, as for example, medially crosswise of their length, and packed and carried in such improved luggage without becoming wrinkled or creased or disarranged in the luggage.

More specifically stated, this invention pertains to an improved arrangement for carrying garments and other items of clothing in hand luggage of conventional size, wherein some of the garments are folded over an improved, freely movable or floating, displacement or folding and storage element having a flexible and resilient garment shaping and restraining portion to compressively coact with the adjacent surfaces of the garment or other items of clothing and the adjacent surfaces of the walls of the suitcase to confine the garments in the suitcase outwardly and/or inwardly of the folding element in a predetermined, smoothly arranged, unwrinkled and uncreased order, and wherein the folding element or frame also functions as a tray and as a dividing unit for the interior of the improved luggage.

Still more specifically stated, this invention pertains to improvements in a freely floating tray-type of garment folding frame or restraining element provided with a suitable resilient, flexible and curved edge or wall section for compressively coacting indirectly with certain walls of the suitcase and directly coacting with the garments to suitably confine the garments in a predetermined shape retaining position and condition outwardly of the folding frame, and to compressively grip other garments within the frame whereby to prevent undesirable wrinkling, creasing or shifting of the garments or other restrained articles of clothing while confined in the luggage, and to provide a tray-type element for supporting as well as positioning other items of clothing or toiletry and to separate other items from the folded garments when confined in the closed suitcase as well as when the suitcase is opened.

Various kinds of luggage, which may be obtained commercially, provide numerous arrangements for supporting or storing garments and other items of clothing in luggage. In certain instances, some of such luggage also includes luggage trays. In some such types of luggage it is common practice to provide for the suspension of a garment or garments on garment hangers supported in the lid or cover section of the luggage, and to fold the garment or garments crosswise of its or their length substantially medially of the garment and deposit the lower or dependent end of the garment or garments in the base or body section of the luggage. Upon closing such luggage, with the suspended garments thus arranged, the garments must fold sharply, generally or approximately, along the line of hinged connection between the body and lid sections of such luggage. Such folding of a garment commonly results in the formation of undesirable wrinkles and creases in the garments. In certain instances, some types of wardrobe luggage have been provided with a rigid and at least partially fixed displace-

2

ment or folding board or tray arrangement as well as with garment restraining straps for coaction with the garments and the walls of the luggage whereby to reduce the tendency of wrinkling the folded garments confined in the luggage and to prevent the shifting of such stored clothing. To some extent such rigid and partially fixed garment displacement or folding elements could function to achieve a limited degree of success in the prevention of wrinkling of folded garments confined in luggage, and the retaining straps can normally prevent the shifting of certain items of clothing.

However, the rigid as well as the partially fixed aspects of such restraining and folding elements and the fixed restraining strap arrangements do not permit the satisfactory use thereof in luggage in such instances wherein the number of garments to be folded and suspended in the luggage as well as other items of clothing to be stored is varied from time to time. It is common practice in the construction of such conventional luggage to provide rigid walls for the luggage and rigid walls as well as positioning fixtures for the garment displacement or folding elements. In such instances, the space provided between the walls of the luggage and the contained rigid garment displacement or folding and storage element will satisfactorily accommodate and function properly only with a predetermined fixed thickness of folded garments as well as a predetermined fixed volume of other clothing. An increase in the number of garments stored in the fixed available space will overcrowd the luggage and will, due to excessive pressures developed upon closing of such overcrowded luggage, produce undesirable wrinkling or creasing of the garments and clothing. Similarly, a decrease in the number of garments and other items of clothing from that sufficient to satisfactorily fill the garment and clothing space between the walls of the case and the displacement unit and the interior of the displacement unit in such conventional luggage will result in loose and unsatisfactory confining of the garments and clothing in the case. Consequently, it is apparent, that in luggage provided with garment restraining or folding elements which are fixed in position and/or which are fixed in size so as to preclude increasing or decreasing the storage space for garments and other items of clothing in luggage, it is impossible from time to time to secure satisfactory storage in the luggage of varying numbers of garments and other items of clothing.

The prior art does not provide luggage including the provision of self adjusting, freely floating, flexible and resilient garment displacement or folding elements for coacting inwardly and outwardly thereof with garments and other items of clothing and indirectly with the walls of the luggage, to satisfactorily, from time to time, enable the confining of varying number and quantity of folded garments and other items of clothing in wardrobe type luggage. Neither does the prior art teach or disclose arrangements for the application of a substantially uniform ironing or smoothing and confining pressure upon stored garments along the fold zone to prevent the formation of wrinkles or creases, as well as to restrain the movement of the garments and other items of clothing within the luggage case, all of which are provided by the present invention.

It is, therefore, the primary objective of this invention to provide improvements in wardrobe type luggage and the like; in which there is provided a freely floating, self adjusting garment confining and folding element having a resilient and flexible garment contacting and supporting portion adapted to coact with the stored garments and other items of clothing and coact indirectly with the walls of the luggage to automatically and simultaneously adjust the space for folded garments and other items of clothing within the luggage to properly accommodate

the garment or garments and other items of clothing stored in the luggage while applying a yielding but substantially uniform confining pressure, and where necessary a smoothing pressure, upon the garment or garments along the fold zone thereof and to apply a restraining pressure on other items of clothing and to function in that manner upon any number of garments or items of clothing stored in the luggage, within the operating capacity of the luggage; in which the garment displacement or folding element, upon being appropriately placed in operating position in the luggage, will automatically adjust itself in operative position to provide the necessary confining room for the stored folded garments along the fold zone, and to apply a substantially uniform smoothing and confining outward pressure to the garment or garments as the case may be, within the storage range of the luggage, and to apply an inward restraining pressure upon the other items of clothing stored in the restraining element; in which the garment displacement or folding element is of such construction and is so arranged in the luggage as to directly or indirectly coact with the inner surfaces of the luggage and adjacent surfaces of confined garments and other items of clothing that as a result of the confining pressure applied by the opposed body and lid sections of the luggage upon the closing of the luggage, the restraining and folding element will automatically tend to maintain itself in satisfactory operative position; in which the restraining and garment folding element may also function as a tray for toiletries or similar small articles stored in the luggage and separated from the suspended garments; in which the restraining or folding element may also function as a clothing or other item positioning device and as a divider for the space within the luggage; in which the fixed capacity and rigidly positioned luggage trays and restraining straps have been eliminated; in which a single tray-like element having a flexible and resilient wall section is used to divide the storage space within the luggage into different zones, to position certain items of clothing within the luggage and to simultaneously apply an outwardly directed confining pressure to suspended garments and an inwardly directed restraining or confining pressure on other items of clothing supported by the improved tray.

The foregoing and other objectives, important new and novel and useful features and advantages of this invention will become more apparent and be more easily understood upon examination of the following description thereof and the accompanying drawings and appended claims. It should, however, be understood that, without desire of limitation, the preferred embodiment of this invention will be described and illustrated as improvements pertaining to a wardrobe type suitcase and suitcase tray. Certain changes and variations may suggest themselves to those skilled in the pertinent arts, which changes may not, however, depart from the spirit of this invention and may come within the scope of the appended claims.

In the accompanying drawings:

Figure 1 is a perspective view illustrating an embodiment of the invention in a rigid, rectangular wall type of wardrobe suitcase;

Figure 2 is an elevational, transverse sectional view, of a suitcase of the general type illustrated in Figure 1 of the drawings and embodying the present invention;

Figure 3 is an elevational end view, partially in broken away section, illustrating the embodiment of this invention in a closed suitcase of the general type illustrated in Figures 1 and 2 of the drawings;

Figure 4 is an illustration of the invention similar to that shown in Figure 3 of the drawings but wherein the suitcase has been provided with curved front and rear edges to provide a case having front and rear wall portions generally conforming to the curvature of the flexible wall of the garment restraining element within the case;

Figure 5 is a perspective view similar to the view shown in Figure 1 of the drawings and illustrating the adaptation of the invention for use in connection with long flared garments which must be folded around the restraining element from various sides thereof;

Figure 6 is a perspective view of a modified form of the improved tray and garment restraining and folding element, having hand grip provisions in its end edges;

Figure 7 is an end view of a further modified form of the improved garment restraining element and suitcase tray having a transverse, resilient, flexible, upwardly and inwardly curved garment contacting wall along two opposite edges whereby the tray is made reversible, and having hand grip and material limiting means for limiting the bending motion of the curved and flexible garment contacting walls;

Figure 8 is a perspective view of another modified form of the improved garment restraining and folding element formed of a framework of resilient and flexible material having a suitable covering jacket.

Referring to the drawings in which like elements are identified by like numerals, and referring particularly to Figure 1 of the drawings, 1 represents the base or body portion of a wardrobe type of suitcase or hand luggage of generally rectangular configuration, having an open top defined by the upwardly extending, opposed, vertical end walls and side walls which are joined to the flat, horizontal bottom wall of the base section of the case, as viewed in Figure 1 of the drawings. The complementary, substantially rectangular lid section 2 which, when the case is closed, has downwardly extending, opposed end and side walls, complementary to the corresponding walls of the base section 1, which defines the open lower portion of the closed lid section 2 when the case is closed. The lid section 2 is hinged to the base section 1 by suitable hinge elements 3 along the juxtaposed edges of the rear side walls of the base section 1 and lid section 2. A carrying handle 4 is suitably secured to the front wall of the base section 1. Locking means 5 are provided on the front walls of the sections 1 and 2.

When the case is opened the lid section 2 is supported by the hinges 3 substantially vertically at the upper end of the rear wall of the base 1 and stabilized in that position by a collapsible brace element 6. A bracket element 7, for supporting suit hangers 8, is secured to the inner surface of the lid section 2 adjacent the mid portion of the upper front side wall of section 2, as viewed in Figure 1, of the drawings. A garment 9, such for example, as a man's suit, may be draped over a hanger 8 and suspended in the lid section 2 with the dependent, lower half portion of the garment disposed on the bottom wall of the lower section 1 of the improved case. As thus arranged the garment 9 overlies the line of hinged juncture of the sections 1 and 2 of the improved case at a position relatively remote from the normal drape of the garment or at approximately the medial portion of the garment vertically thereof, along which medial section or portion the garment must fold crosswise of the garment upon the closing of the improved case.

To satisfactorily accomplish the mentioned folding of the garment 9, and to avoid the undue wrinkling or creasing of the garment, and to securely hold and partially support the garment smoothly with a yielding gentle pressure, there is provided a folding frame and restraining element 10. The element 10 may be formed of any suitable material, as for example, cast, extruded, molded or fabricated plastic. Similarly, it may be appropriately formed of any suitable metal, or may be formed of a combination of suitable materials and may, if desired, be covered with a jacket or sheath.

The restraining or folding element 10 is, very generally stated, preferably of a configuration, contemplating a plan view outline, similar to that of the general plan view outline of the base of the improved case. In the

preferred embodiment of the invention, illustrated in Figure 1 of the drawings, such outline of the plan view would be generally rectangular in shape, with the width or transverse or crosswise dimension of the folding and restraining element 10 being somewhat less than but substantially as great as the crosswise or transverse dimension of the interior of the base 1 of the case and with the length or longitudinal dimension of the element 10 being appreciably or substantially less than the length or longitudinal dimension of the case and only slightly longer than the lower dependent portion of the suit 9 resting on the bottom wall of the base section 1 of the case.

In this application a transverse or width or crosswise dimension will be deemed to be a dimension measured from left to right when viewing Figure 1 from a position on the handle side of the case of Figure 1, while a length or longitudinal dimension will be deemed to be a dimension measured from the front or handle side of the case to the hinge side of the case as viewed in Figure 1, and a depth dimension will be deemed to be a vertical dimension as applied to the horizontal case of Figure 1, and will extend for example upwardly from the lower panel of the lower section 1 of the case.

The element 10 in normal use is deposited upon the depending portion of garment 9 in section 1 of the case toward the rear of the case, and is comprised of a substantially horizontal main panel 11 adapted to overlie, and in part rest upon, the dependent portion of the garment 9 disposed in the section 1 of the case on the lower wall thereof. Panel 11, as shown in Figures 1, 2 and 4, of the drawings is preferably formed of suitable plastic material which may, if desired, be transparent and of such thickness or gauge as to provide a substantially rigid, yet relatively thin, panel 11. The downwardly turned or directed front edge or wall section 12 depends from the forward or front edge of panel 11 and is of a height in proportion to the underlying thickness of the stored garments, according to the stored garment capacity of the improved case, so that the extreme lower dependent end of the garment or garments 9 will not be subjected to undue pressure by the main panel section 11 and the weight of articles which may in turn be stored on the tray 10. The wall section 12 also functions as a transverse divider of the space in the lower portion of section 1 of the case.

An upwardly, and outwardly and then upwardly and inwardly and then slightly downwardly and inwardly curved resilient and substantially flexible wall section 13 extends from the rear portion of the main panel section 11 of the folding or tray element 10 in a configuration having a vertical longitudinal cross section in the general shape of a reclining U which is narrower at its mouth than at its mid section. When the garment 9 is suspended in the improved case in the manner illustrated in Figure 1, of the drawings, the folding and shaping element 10 is deposited over the lower dependent end of the garment 9 in the section 1 of the case with the downwardly directed front edge 12 in front of the lower end of the garment 9 and resting on the inner surface of the lower wall of the section 1 of the case with the curved generally U-shaped smooth flexible and resilient rear or transverse wall 13 of element 10 resting on the upper surface of the dependent portion of garment 9 in section 1 of the case and forced into compressive engagement with the adjacent surface of the garment 9 which overlies the rear wall of the section 1 parallel to the line of hinging between sections 1 and 2 of the case. The upwardly and inwardly and the inwardly and downwardly curved portions of the U-shaped section 13 do not compressively engage the garments 9 when the luggage case is open, but as clearly illustrated in Figures 1 and 2, of the drawings, extend into the space generally along or slightly above the plane of juncture between the sections 1 and 2 of the case, which sections of the

case will be occupied by the portions of the garments 9 when the case is closed. The section 13 is of a depth substantially less than the depth of the case when closed.

As illustrated in Figures 1, 2, 3 and 4, of the drawings, the space interiorly of the U-shaped section 13 may be utilized for the storing of compressible garments such as shirts 14, etc., which are to be grasped and held in place in the section 13 when compressed.

Upon closing of the improved case, by the hinged lowering of the section 2 upon the section 1, the garment 9 is folded crosswise of its length, generally along its medial section about the curved wall 13 of element 10. Such folding during such closing operation gradually compressing the resilient and flexible spring-like curved U-shaped element 13 into the position shown in Figures 3 and 4 of the drawings in which position the curved portion 13 of element 10 adjacent the medial portion of the garments 9 in the rear portion of the closed case, applies a yielding upward, downward and rearward pressure to the garments 9 which it engages snugly and maintains in smooth unwrinkled and uncreased arrangement in the improved case in the desired position and order in which the garments were deposited in the case. The inwardly and slightly downwardly directed extreme inner upper portion of the curved element 13 coacts with the overlying portion of the garments 9, and, due to the plan of curvature of the compressed element 13, as illustrated in Figure 4 of the drawings, tends to urge the compressed curved wall 13 rearwardly of the improved case into tight engagement with the portion of the garments 9 in the rear part of the case, and prevents the forward shifting of the tray 10.

Similarly, upon the described compressing or closing type flexing of the curved U-shaped wall section 13 upon the closing of the lid 2 on the base 1 of the luggage case, the shirts or like compressible garments or clothing items 14 are compressed and securely locked in position between the upper and lower branches of the U-shaped curved side wall 13 of tray 10. The clothing items 14 which are thus securely grasped upon the closing of the luggage and the incidental flexing of the branches of the element 13 are automatically released again upon the opening type flexing of the branches of element 13 when the case is subsequently opened.

The resilience and flexibility of the curved wall 13 of the element 10 is substantial such as to adapt it to function satisfactorily as a restraining element to accomplish the hereinbefore enumerated objectives, throughout the entire range of garment capacity of the improved case. The unique garment restraining element is freely floating within the lower section 1 of the improved case and may be shifted longitudinally, vertically and slightly transversely with respect to the section 1 during the process of packing the case. However, when the case is closed and the resilient curved wall 13 is compressed vertically with respect to the case, as illustrated in Figures 3 and 4 of the drawings, the element 10 is releasably locked in position in the closed case.

Due to the flexibility of the curved wall 13 of restraining element 10 a garment storage space of substantially uniform thickness, measured from front to back of the stored garments, is obtained, and the garments are not unduly compressed.

The dependent wall 12 of tray 10 also functions as a divider whereby to protect the lower ends of the garments 9 from items such as, for example, cosmetic case 15 stored in section 1 of the case between the wall 12 and the adjacent front wall of the case 1 as illustrated in Figure 2 of the drawings. Slight forward or rearward that is longitudinal adjustment of the tray 10 during the packing of the luggage will permit the use of the wall 12 to urge the case 15 against the front wall of section 1 of the luggage case to thus retain the case 15 in position.

The downwardly directed dividing and supporting wall of tray 10 may also be directed slightly inwardly to un-

derlie the main panel 11 of the tray 10 as illustrated at 16 in Figure 3 of the drawings. Such an arrangement permits the use of the front edge of the tray 10 and the thus tilted wall 16, as a retainer for shoes 17 or like items which arrangement due to the overlapping arrangement between the front edge of tray 10 and inclined wall 16 and the shoe 17 in the manner illustrated in Figure 3 of the drawings confines or retains the shoe 17 in position in the bottom section 1 of the improved case between the front edge of the tray 10 and the adjacent front side wall of section 1 of the case. Obviously, slight forward or rearward adjustment of the tray 10 will permit the adaptation of the use of the improved tray for retaining shoes of different sizes in the described manner.

The garment storage cases of Figure 4 of the drawings, having the curved front and rear edges emphasizes the garment storage space of uniform depth between the walls of the case and the complementary surfaces of the restraining element 10. The increase or decrease in depth of garment storage space between the element 10 and the lower and upper walls respectively of the sections 1 and 2 is obtained as a result of the flexing of the curved wall 13 to decrease or increase respectively the space between the branches or sides of the U-shaped curved section 13. Similar adjustment in garment storage space between the wall 13 and the rear wall in the case is obtained by suitable forward or rearward shifting of the element 10.

Obviously, as the space for the storage of folded garments between the U-shaped section 13 and the adjacent surfaces of the sections 1 and 2 of the case is increased, the space for the storage of compressible clothing items 14 between the branches of the U-shaped section 13 is simultaneously and automatically decreased and vice versa.

As is clearly illustrated in the drawings, the upper surface of the garment folding or tray element 10, may be used as a tray for the storage of other items of clothing or toiletry in such a manner that they have the least possible contact with the stored garments 9.

Several embodiments of the invention have been disclosed in and described with respect to Figures 1, 2, 3 and 4 of the drawings in connection with the possible use of the invention for the storage of garments, such as men's suits and the like in wardrobe suitcases. Due, however, to the completely free floating arrangement of the tray or folding and restraining element 10, which is not only of less dimension than the case transversely of the case but also of less dimension than the case longitudinally of the case, the invention is also well adapted for use in the similar storage of bulkier and larger garments such as ladies' dresses, including dresses having flared or wide skirts.

In Figure 5 of the drawings there is illustrated an arrangement for the storage of a dress 18 in the improved suitcase wherein the depending flared skirt portion of the dress 18 is stored in the lower section 1 of the case. It will be observed that the upper portion of the dress 18 is suspended on a hanger in the lid section 2 of the case and the flared skirt is deposited over section 1 of the case. After the folding and restraining element 10 is placed in folding and restraining position in section 1 of the case, the flared sides of the skirt, which normally extend beyond the ends of the folding tray, are folded inwardly and over the tray, overlapping one another, thereafter the lower portion of the skirt is folded inwardly and overlapped over the previously folded flared side portions of the skirt over the top of and along the front edge of the folding tray 10.

In certain instances, particularly for the storage of thin garments such as ladies' dresses, and to avoid creasing such thin garments, it may not be desired to provide the restraining element 10 with a relatively thin dependent downwardly directed front wall or flange 12. In such instances the front end of panel 11 may be provided with a downwardly and inwardly rolled edge 19 which, due

to its relatively extensive contact with a stored dress or similar long garment, will prevent creasing the dress along the line of contact with the rolled edge 19.

In other instances, the element 10 may be composed of only the main panel section 11 and curved rear wall section 13 as illustrated in Figure 6 of the drawings. Such a simplified element 10 obviously requires the minimum space within the improved case, and any of the trays 10 may be provided with cut-out hand-grip arrangements 20 in the end edges of panel 11, as illustrated in Figure 6 of the drawings.

In certain instances, particularly in instances wherein the restraining element 10 is to be used in a case having rounded front and rear upper and lower edge sections, it may be desirable to use a tray having curved resilient and flexible front and rear wall sections 13 and 21 respectively as illustrated in Figure 7 of the drawings. Such a tray would also incorporate into the front section of the suitcase the improved flexible and resilient garment support arrangement which has hereinbefore been described in regard to a tray 10 having only the rear flexible element 13. The tray having both front and rear flexible edges 13 and 21 may be used to particular advantage for certain types of longer garments. Such a tray would yieldably support such longer garments against both the front and rear walls of the case. The variation of the tray 10 illustrated in Figure 7 of the drawings is also provided with bar-like hand-grip and motion limiting elements 22 which are secured to the panel 11 at each end thereof intermediate the flexible and inwardly curved wall sections 13 and 21. The elements 22 are of such a height and of such a length as to enable easy grasping thereof when used as handles for the tray 10, and so arranged as to suitably underlie the inwardly extending portions of the curved wall sections 13 and 21 in such a manner as to also function as a stop element to limit the maximum downward flexing of the curved wall sections 13 and 21, thereby to prevent the possible crushing of the curved portions of sections 13 and 21.

In Figure 8 of the drawings there is illustrated a variation of the improved garment restraining element 10, wherein the element 10 is formed of a covered or jacketed stay-like frame work consisting of relatively rigid, straight, transverse stays 23 and overlapping, longitudinal stays 24 secured together at the points of overlapping. Each of the longitudinal frame elements or stays 24 is provided at one end with a resilient flexible end portion having the same general curvature as hereinbefore described with respect to wall section 13 of tray 10 as illustrated in Figure 1 of the drawings. The transverse frame or stay-like elements 23 are so positioned as to define generally the front, the rear and the upper and lower edge portions of the variation of tray 10 illustrated in Figure 8 of the drawings. The frame or stay-like elements 23 and 24, which may preferably consist of suitable material, such as tempered steel or resilient and flexible plastic, when joined in the manner illustrated in Figure 3 of the drawings, may be provided with any suitable form of enclosing sheath or jacket 25 to complement the interior of the improved case and tray combination.

In each instance any of the variations of the tray 10 illustrated in the drawings may be provided with hand-grip elements, one variation of which is illustrated in Figure 6 of the drawings, wherein the transverse opposite cut-outs 20 in the ends of the panel section 11 of the element 10 may function as a convenient hand-grip arrangement. Similarly, any of the illustrated variations of the tray 10 may, if desired, be provided with the combined hand-grip and flexible wall motion limiting handles 22, illustrated in Figure 7 of the drawings.

From the foregoing description of this invention and from the accompanying drawings, it will be apparent that this invention realizes the introductory enumerated objectives respecting the improved suitcase and tray therefor, which improved hand type luggage possesses the

hereinbefore introductory listed advantages and provides a new, unique and useful arrangement and combination of elements in luggage which, due to the unique configuration and structure of the combined tray and garment folding and restraining element and the coaction thereof directly or indirectly with the inner surfaces of the case, enables the utilization of the maximum amount of space in the luggage for the storage of garments and other items usually carried in such luggage in the unique and novel manner hereinbefore described.

Having thus described and illustrated the preferred embodiment of several variations of this invention in an improved suitcase and tray therefor, the invention is not to be interpreted as being restricted to the specifically illustrated and described embodiments as set forth in the drawings and as hereinbefore described, except insofar as is necessitated by the disclosure of the prior art and the appended claims.

The invention is hereby claimed as follows:

1. A wardrobe type case including garment hanger means upon which a garment may be hung in the case for the storage of a garment comprising, in combination, a body section having a bottom panel hingedly joined along an edge thereof to a lid section having a top panel, each of said sections having end walls and side walls joined to the associated panel and having the free edges of the corresponding walls adapted to engage one another when the lid section is closed upon the body section, a floating and self adjusting type of garment folding and tray element having a resilient and substantially flexible wall section along one edge thereof around which a garment may be folded when said case is closed, said folding and tray element having overall length or longitudinal and depth dimensions less than the corresponding dimensions of the interior of said case when closed and having a width or transverse dimension less than but substantially as great as the width or transverse dimension of the interior of said case, and said resilient and substantially flexible wall section of said folding and tray element in the absence of flexing pressure having a generally U-shaped cross section longitudinally of said folding and tray element with the convex apex portion of said U-shaped cross section being disposed adjacent the line of hinging between said body section and said lid section, and having said U-shaped cross section portion of said tray element partially flexed by the folded garment when said case is compressively closed, whereby to maintain said folded garment in predetermined position and condition of folding.

2. A suitcase comprised of a body section and a lid section, each of said sections having end walls and side walls and having bottom and top panels respectively and having the free edges of corresponding walls adapted to engage one another when the lid section is closed upon the body section, hinge means joining said lid section to said body section along the juxtaposed edges of two corresponding side walls, a garment folding frame and tray element about which a garment may be folded in said suitcase, said frame having a transverse dimension substantially as great as but less than the transverse inner dimension of said suitcase and having a longitudinal dimension substantially less than the longitudinal dimension of said suitcase, said frame and tray element when uncompressed having an upwardly and outwardly and thence upwardly and inwardly and thence downwardly and inwardly curved and resilient and substantially flexible wall section substantially parallel to the line of hinged juncture between said body section and said lid section and adapted to be compressively flexed between the folds of a garment by said bottom and top panels when said suitcase is closed, said frame and tray element when said flexible wall section is uncompressed having a maximum depth substantially less than the depth of the interior of said case when closed.

3. A wardrobe type case for the storage of garments

comprising, in combination, two case members hingedly secured together along two juxtaposed edges and adapted to form an openable closed case, a floating displacement frame element in the case having a resilient and substantially flexible curved wall section along an edge thereof substantially parallel to the line of hinging of said case members and having the convex side of said curved wall section adjacent to said line of hinging, said displacement frame element having a width or transverse dimension less than but substantially as great as the transverse inner dimension of the case and having a longitudinal dimension substantially less than the longitudinal inner dimension of said case and being adapted to be spaced from all side and end walls of the case when closed, the extent of the spacing between the inner surfaces of the case and the adjacent surfaces of said displacement frame element measured in the plane of flexing of the frame element when the case is closed and said resilient curved wall is flexed as a result of the compressive closing of said case being determined by the thickness of the contiguous portions of the stored garment between said inner surfaces of the case and the adjacent surfaces of the displacement frame element.

4. A suitcase comprising, in combination, a body section, a lid section, hinge means securing together said body section and said lid section, bracket means in said lid section for supporting garment hangers upon which garments may be suspended, a floating and self adjusting tray element within said body section, said tray element having a substantially flexible and resilient curved wall section overlying a portion of the tray element and being parallel to said hinge means and unflexed when said case is open and adapted to engage the garments suspended upon hangers in said case and to press said garments toward the adjacent inner surfaces of said sections when said case is compressively closed and said resilient curved wall section is flexed by the pressure of the opposed body section and lid section, said tray element having a transverse dimension less than but substantially as great as the inner transverse dimension of the suitcase and having a longitudinal dimension substantially less than the longitudinal dimension of the suitcase.

5. Luggage equipment comprising, in combination, a case having matched lower portion and lid portion hinged together along one set of juxtaposed edges, said case being shaped to have the lower portion rest on a substantially horizontal flat surface and when opened to have the hinged lid portion disposed in a substantially vertical arrangement, bracket means secured to said lid portion adjacent the top of the inner face of said lid portion for suspending upon hangers the upper ends of garments with the body portions of such garments extending downwardly into said lower portion of the case and then extending longitudinally through at least a section of the opened lower portion of the case, a garment folding frame disposed transversely across and overlying and resting upon the lower ends of the suspended garments laid on the inner surface of said lower portion of the case, said garment folding frame having a resilient and substantially flexible rounded rear wall section of a size adapted when the case is closed to be flexed by the pressure of the opposed said lower portion and said lid portion of said case acting through said garments and yieldably displaced and press against the contiguous portions of the suspended garments urging them into engagement with adjacent inner surfaces of the luggage case and being unflexed and rounded when the case is open.

6. A suitcase comprising, in combination, a body section, a lid section, means for supporting garments in said lid section and a space for depositing another item of apparel in the body section, a floating tray element in said suitcase, said tray element having along one side thereof a resilient and substantially flexible curved wall section overlying a portion of said tray element and having along the opposite side thereof a downwardly

directed wall section, said curved wall section being unflexed when said suitcase is open and being adapted to engage the garments supported in said case throughout their adjacent transverse surfaces and to press said garments toward the adjacent inner surfaces of the sections of said case when said curved wall is flexed by the pressure applied thereto through said garments by said body section and said lid section upon the closing of the suitcase, said downwardly directed wall section being adapted to be moved into engagement with said other item of apparel and graspingly urging it against the adjacent inner surface of said suitcase, whereby when said case is closed and said tray element locked in position by the compressing of said flexible curved wall section said other item of apparel is locked in position by the engagement with the said downwardly directed wall section and the adjacent inner surface of said suitcase.

7. A suitcase arrangement according to claim 6, wherein in said downwardly directed wall section is also inwardly directed with respect to the body portion of said tray element, and wherein said other item of apparel has a surface adjacent to said downwardly directed wall section complementary thereto, whereby when said tray element is moved into engagement with said other item of apparel the downwardly and inwardly directed wall section will overlappingly engage the complementary surface of said other item of apparel and upon the closing of said suitcase will exert both a downward and sideward confining pressure against the other item of apparel.

8. A garment confining device comprising, in combination, a body section having a coverable open top, a cover section hinged to the body section and adapted to cover the open top of the body section, a garment hanger bracket at the free end of said cover section interiorly thereof, garment hanger means detachably supported on said bracket whereby garments may be suspended along the inner side of said cover section and the rear wall of said body section with the lower portions of such suspending garments resting upon and overlying a portion of the inner surface of the bottom of said body section, garment restraining and shaping means adapted to overlie and rest upon the upper surface of the lower portions of such garments in said body section, said garment restraining and shaping means being otherwise normally free to move longitudinally and transversely and vertically with respect to the interior of said bottom section when said cover section is in open position, said garment restraining and shaping means having adjacent the line of hinging of said body section and said cover section a curved and freely and substantially flexible and resilient wall portion of a generally U-shaped cross section in a plane substantially perpendicular to the axis of hinging between said body section and said lid section and having one branch of the U-shaped curved wall portion overlying a portion of a main panel section of the restraining and shaping means with the free end of the overlying portion nearer said main panel section than is a portion of the overlying section intermediate the free end and the apex of the generally U-shaped curved wall portion, said generally U-shaped curved wall portion being unflexed when said curved section is in open position and being adapted for engagement with the inner surface of the suspended garments opposite the rear wall of the said bottom section and between the lower portion of said body section and said cover when said curved wall portion is flexed by the compressive force applied thereto through said garments by said body section and said cover for pressing the contacted portions of such garments in unwrinkled form tightly against the rear wall of said bottom section and preventing the wrinkling of the garments and maintain the garments in predetermined position in said case.

9. A luggage case for the storage of a folded garment comprising, in combination, an open topped body section, an open bottom lid section, hinge means securing together

said body section on said lid section, bracket means in said lid section for supporting a garment hanger upon which a garment may be suspended with the upper portion of said garment positioned in said lid section and with the lower portion of said garment deposited in said body section and with the medial portion of said garment folded generally along the hinged line of juncture between said body section and said lid section, a floating type tray disposed at least partially within the body section of the luggage case, said tray having a transverse dimension less than but substantially as great as the interior transverse dimension of said case and having a longitudinal dimension substantially less than the longitudinal dimension of said case and having a resilient and substantially flexible curved wall section along one side thereof overlying a portion of a base section of said tray and positioned generally parallel to said hinge means, said curved wall section of said tray when said case is open normally extending away in unflexed condition from said base section a distance in excess of the available space intermediate the position to be occupied by the folded portions of a garment when the luggage case is closed, said tray being adapted to be deposited upon the lower portion of the garment with the curved wall section engaging the medial and adjacent portion of the garment, said curved wall section of said tray being adapted upon the closing of said case whereby a flexing pressure is applied by said body section and said lid section through said garment to said curved wall section to compressively engage with a yieldable pressure the adjacent upper and lower and medial portions of the garment stored in said case and compressively urge those portions of the garment toward the adjacent inner surfaces of said case.

10. A suitcase comprising, in combination, a body section having bottom and side surfaces, a lid section hinged to said body section, and a floating type of garment restraining and folding and storing tray element disposed within said body section, said tray element having a longitudinal dimension substantially less than the interior longitudinal dimension of said body section and having a transverse dimension less than but substantially as great as the interior transverse dimension of said body section and having along its front edge a downwardly extending wall element engaging the adjacent surface of the bottom of said body section and spaced from the adjacent front side surface of said body section, whereby said downwardly extending wall element supports the forward portion of said tray element and segregates the space within said body section and below said tray element from the space intermediate said downwardly extending wall element and the adjacent front side surface of said body section.

11. In a suitcase the combination of, a body section, a lid section, each of said sections having corresponding end walls and side walls and a top panel in the lid section and a bottom panel in the body section and having the free edges of the several walls adapted to engage one another when the lid section is closed upon the body section, each of said end walls being joined to the associated panel member by an outwardly convex curved edge portion, a floating type garment folding and restraining element within said suitcase, said folding and restraining element having a transverse dimension less than but substantially as great as the transverse inner dimension of said suitcase and having a longitudinal dimension substantially less than the longitudinal dimension of said suitcase, and having along one edge thereof parallel to one of said side walls a resilient and substantially flexible wall section having a generally U-shaped transverse cross section when compressively flexed, said U-shaped cross section being similar to but of lesser dimensions than the corresponding generally U-shaped transverse cross section of the adjacent portion of the suitcase when closed, whereby when said flexible U-shaped wall section of said restraining element is compressed by the applica-

tion of flexing pressure through a garment by said body section and said lid section when closed a generally U-shaped garment receiving space of substantially uniform transverse cross section is provided intermediate the U-shaped portion of said restraining element and the adjacent inner surfaces of said suitcase when closed.

12. In a luggage case, a tray having a multi-sided base section having at one side thereof an integrally formed curved wall section overlying the adjacent portion of said base section, said curved wall section being resilient and substantially flexible and shape retaining in the absence of flexing pressures and shape resuming upon the release of flexing pressure and being adapted by flexing to engage garments folded about said curved wall section and stored in said case and apply a yieldable confining pressure to said stored garments throughout their transverse extent for urging said garments into predetermined stor-

age space in said case when said tray is compressively flexed between the body portion and lid portion of said case by the application of pressure to the curved wall section through said garments.

13. In a tray for a luggage case, a multi-sided substantially flat base section having at one side thereof an integrally formed curved wall section overlying the adjacent portion of said base section, said curved wall section being resilient and shape retaining in the absence of flexing pressure and being shape resuming upon the release of flexing pressure.
